John B. Murphy Jr. Attorney

UNITED STATES PATENT OFFICE.

ALVA K. HINCHMAN, OF PHILADELPHIA, PENNSYLVANIA, ASSIGNOR, BY MESNE ASSIGNMENTS, OF ONE-FOURTH TO CHARLES H. QUIMBY AND ONE-FOURTH TO CHARLES H. MORTON, BOTH OF PHILADELPHIA, PENNSYLVANIA.

EXPANSION VALVE AND GOVERNOR.

1,406,014.

Specification of Letters Patent. Patented Feb. 7, 1922.

Application filed March 22, 1919, Serial No. 284,313. Renewed December 7, 1921. Serial No. 520,717.

To all whom it may concern:

Be it known that I, ALVA K. HINCHMAN, a citizen of the United States, residing at Philadelphia, in the county of Philadelphia and State of Pennsylvania, have invented 5 certain new and useful Improvements in Expansion Valves and Governors; and I do hereby declare the following to be a full, clear, and exact description of the invention, 10 such as will enable others skilled in the art to which it appertains to make and use the same.

This invention relates to improvements in expansion valves and governors and has for 15 one of its objects the provision of means for controlling fluid or air pressure so as to keep the pressure at a predetermined degree from a high pressure source.

Another object of this invention is the 20 provision of high and low pressure chambers and double acting piston, whereby a predetermined pressure can be kept at and from the low pressure chamber, while the same is fed from the high pressure chamber.

25 A further object of this invention is the provision of means whereby the piston of the high pressure chamber can be balanced so as to reduce the pressure in and from the low pressure chamber.

30 A further object of this invention is the provision of an auxiliary controlling means adapted to admit high pressure from the source directly into the low pressure chamber as desired so as to further reduce the 35 pressure in and from the low pressure chamber.

35 A still further object of this invention is the provision of an expansion valve and governor of the above stated character, 40 which shall be simple, durable and efficient, and which may be manufactured and sold at a comparatively low cost.

With these and other objects in view as 45 will become more apparent as the description proceeds, the invention consists in certain novel features of construction, combination, and arrangement of parts, as will be hereinafter more fully described and claimed.

50 For a complete understanding of my invention, reference is to be had to the following description, and accompanying drawings, in which:

Figure 1 is a vertical sectional view of an

expansion valve and governor constructed in 55 accordance with my invention.

Figure 2 is a similar view illustrating a modified form of my invention.

Referring in detail to the drawing, the 60 numeral 1 indicates a casing having formed in its lower end an intake port 2 which is adapted to be connected in any well known manner to a fluid or air high pressure source 3. The inner end of the intake port 2 has formed thereon a valve seat 4 which 65 is located within a high pressure chamber 5 and is adapted to receive during the operation of the device a valve 6 formed on one head of a double acting piston 7. A low pressure chamber 8 is formed in the upper 70 portion of the casing 1 and has its upper end closed by a removable cap or cover 9 that is threaded or otherwise secured in the upper end of the casing. The high and low pressure chambers are divided by a web or plate 75 10 which is threaded in the wall of the casing as shown at 11 and is provided with a double packing gland 12, one portion of which is disposed in the high pressure chamber, while the other portion is disposed in 80 the low pressure chamber and slidably receives the stem 13 of the double acting piston 7, permitting the heads 14 and 15 to work in the low and high pressure chambers. The head 14 which is located in the low pressure 85 chamber has a ratio of about four to one of the head 14 which is located in the high pressure chamber. The low pressure chamber is of a size greater than the high pressure chamber according to the difference in the 90 sizes of the piston heads 14 and 15.

Passages 16 and 17 are formed in the casing 1 and lead from the high pressure chamber to the upper end of the low pressure chamber so that the fluid or air pressure 95 can enter the low pressure chamber from the high pressure chamber when the double acting piston 7 is up and as the pressure against the piston head 14 overcomes the pressure against the piston head 15, which 100 is less than the pressure against the piston head 14 owing to the size of the same over the piston head 15 the latter is forced downwardly seating the valve thereof against the valve seat and at the same time closing the 105 lower ends of the passages 16 and 17. The fluid or air pressure in the low pressure chamber which is at the desired degree then

passes outwardly therefrom by way of discharge pipes 18 leading from the upper end of said low pressure chamber and which are adapted to be connected to the device that is to receive the liquid or air pressure at the desired degree. As soon as the pressure in the low pressure chamber starts to decrease, the high pressure against the piston head 15 or the valve thereof moves the piston upwardly permitting the liquid or air pressure to enter the high pressure chamber and pass into the low pressure chamber by way of the passages 16 and 17, thereby keeping an even pressure in the low pressure chamber at all times and to the device that is using the liquid or air pressure at the predetermined degree.

An adjusting rod 19 passes through the cap or cover of the casing and is screw threaded therein and is provided with a head 20 so that the stroke of the piston 7 can be regulated as desired. A lock nut 21 is mounted on the rod 19 and is adapted to be turned into engagement with the cover or cap for locking the rod at various adjusted positions and which is provided with handles 22 so that the same can be readily turned.

The passage 17 is provided with a branch 23 which leads to an auxiliary chamber 24 formed between the piston head 14 and the web or plate 10 and is controlled by a needle valve 25 having a lock nut 26. By opening the needle valve, fluid or air pressure will be admitted to the auxiliary chamber which will balance the piston and thereby reduce the amount of pressure required in the low pressure chamber in order to seat the valve of said piston. This is provided for in case it is desired to use a lower liquid or air pressure from the low pressure chamber.

The passage 17 is provided with a branch 27 which leads to the intake port of the casing and is provided with a needle valve 28 having a lock nut 29 whereby said branch can be controlled. By opening the valve 28 high pressure from the source can be admitted directly to the low pressure chamber, even when the valve is closed thereby permitting high pressure from the source to pass directly out through the outlet ports 18.

Referring to Figure 2 which illustrates clearly my modified form of invention, the casing 30 has formed in its bottom an intake port 31 adapted to be connected to the high pressure source 3 and is equipped with a valve seat 32 adapted to be engaged by a valve 33 carried by the head 34 of a double acting piston 35. The double acting piston 35 operates within high and low pressure chambers 36 and 37. A piston 38 is carried by the stem of the double acting piston 35 and is located in the low pressure chamber 37 and is of a ratio greater than that of the piston 34. The high and low pressure

chambers vary in sizes according to the ratio of the pistons and are separated by a plate 39 secured to an annular shoulder formed within the casing 1 by bolts 40. The plate 39 is provided with a stuffing box 41 to slidably receive the stem of the double acting piston 35.

Passages 42 and 43 are formed in the casing 30 and communicate with the high and low pressure chambers at points below and above their respective pistons so that when the pressure within the low pressure chamber decreases, the high pressure through the intake port 31 may unseat the valve and pass into the low pressure chamber from the high pressure chamber, thereby seating the valve when the pressure within the low pressure chamber exceeds the pressure within the high pressure chamber. A branch 44 leads from the passage 43 to the intake port 31 and is controlled by a needle valve 45, so that the high pressure directly from the intake port may be conveyed to the low pressure chamber when desired though the valve is closed. A branch 46 is formed in the casing 30 and leads from the passage 43 to an auxiliary chamber 47 formed by the plate 39 and the upper face of the piston 34 providing a construction wherein the degree of pressure required to seat the valve may be lessened if desired by admitting pressure from the intake port directly into the auxiliary chamber. The branch 46 is controlled by a needle valve 48.

A branch 49 leads from the passage 43 to an auxiliary chamber 50 formed by the plate 39 and the piston 38 within the low pressure chamber so that the pressure can be admitted from the intake port 31 into the chamber for the purpose of increasing the amount of pressure required to seat the valve 33. The branch 49 is controlled by a needle valve 50.

The casing 30 is closed by a removable cap 51 secured in position by means of nuts 52 and is provided with an adjusting screw 53 for limiting the movement of the double acting piston 35. The cap 51 is provided with outlet ports 54 adapted to be connected to a device employing low pressure.

While I have shown and described the preferred embodiment of my invention, it will be understood that minor changes in construction, combination and arrangement of parts may be made without departing from the spirit and scope of the invention as claimed.

Having thus described my invention, what I claim is:—

1. A device of the character set forth comprising a casing having high and low pressure chambers and said high pressure chamber having an intake port provided with a valve seat, discharge pipes connected to the low pressure chamber, said casing having passages leading from the high pres- 130

sure chamber to the low pressure chamber, a double acting piston in said casing for opening and closing the passages, and a valve secured to said piston and adapted to 5 engage the valve seat when the piston closes the passages.

2. A device of the character set forth comprising a casing, a web in said casing forming low and high pressure chambers, said 10 high pressure chamber having an intake port provided with a valve seat, discharge means for the low pressure chamber, said casing having passages leading from the high pressure chamber to the low pressure chamber, a 15 piston stem slidable in the web, a head formed on each end of the piston stem and located in said chambers, one of said heads forming between itself and the web an auxiliary chamber, said casing having a second 20 passage communicating with one of the first named passages and the auxiliary chamber, a valve in said second named passage, one of said piston heads closing the first named passages when in one position, 25 and a valve formed on the last named piston head and adapted to engage the valve seat when the piston closes the first named passages.

3. A device of the character set forth comprising a casing, a web in said casing forming low and high pressure chambers, said 30 high pressure chamber having an intake port provided with a valve seat, discharge means for the low pressure chamber, said casing having passages leading from the high pressure chamber to the low pressure chamber, a piston stem slidable in the web, a head formed on each end of the piston stem and located in said chambers, said 35 heads forming between themselves and the web auxiliary chambers, said casing having auxiliary passages communicating with the first named passages and the auxiliary chambers, valves in said auxiliary passages, 40 one of said piston heads closing the first named passages when in one position, and a valve formed on the last named piston head and adapted to engage the valve seat when the piston head closes the first named 45 passages.

4. A device of the character set forth comprising a casing, a web in said casing forming low and high pressure chambers, said 50 high pressure chamber having an in-

take port provided with a valve seat, discharge means for the low pressure chamber, said casing having passages leading from the high pressure chamber to the low pressure chamber, a piston stem slidable in the web, a head formed on each end of the piston stem and located in said chambers, said heads forming between themselves and the web auxiliary chambers, said casing having auxiliary passages communicating with one of the first named passages, valves in said auxiliary passages, a second auxiliary passage communicating with one of the first named passages and with the intake port of the high pressure chamber below the valve seat, a valve for the second named auxiliary passage, one of said piston heads closing the first named passages when in one of its positions, and a valve formed on the last named piston head and adapted to engage the valve seat when said piston is in a position to close the first named passages.

5. A device of the character set forth comprising a casing, having one end open, a removable cover closing said open end of the casing, a web in said casing forming low and high pressure chambers, said high pressure chamber having an intake port provided with a valve seat, discharge means for the low pressure chamber, said casing having passages leading from the high pressure chamber to the low pressure chamber, a piston stem slidable in the web, a head formed on each end of the piston stem and located in said chambers, a regulating screw 80 adjustably secured to the cover and extending therethrough for regulating the movement of the piston stem, said heads forming between themselves and the web an auxiliary chamber, said casing having an auxiliary 85 passage communicating with one of the first named passages and the auxiliary chamber, a valve in said auxiliary passage, one of said piston heads closing the first named 90 passages when in one position, and a valve formed on the last named piston head for engagement with the valve seat.

In testimony whereof I affix my signature in presence of two witnesses.

ALVA K. HINCHMAN.
